Pasquale Medici, Brooklyn, N. Y., assignor to
United Metal Goods Manufacturing Co., Inc.,
Brooklyn, N. Y., a corporation of New York

Application October 28, 1949, Serial No. 5,766

Term of patent 14 years

(Cl. D42—7)

To all whom it may concern:

Be it known that I, Pasquale Medici, a citizen of the United States, residing at Brooklyn, in the county of Kings and State of New York, have invented a new, original, and ornamental Design for a Clock, of which the following is a specification, reference being had to the accompanying drawing, forming part thereof.

Fig. 1 is a front elevational view of a clock, showing my new design.

Fig. 2 is a side view of Fig. 1.

I claim:

The ornamental design for a clock, as shown.

PASQUALE MEDICI.
